CABINET WATER COOLER

Carter F. Truitt, San Diego, Calif.

Application July 10, 1933, Serial No. 679,725

2 Claims. (Cl. 62—154)

My invention relates to cabinet water coolers, and the objects of my invention are:

First, to provide a cooler of this class wherein the operating portions are entirely enclosed;

Second, to provide a cooler of this class wherein flow of air around and about the water cooling element is facilitated;

Third, to provide a cooler of this class which incorporates a novelly arranged waste water receptacle so as to receive drippings from the water cooling element as well as water from the cup tray or basin associated with the faucet;

Fourth, to provide a cooler of this class which requires no more space than the conventional water cooler, and which may be used in conjunction with bottled water or with a filter;

Fifth, to provide a water cooler of this class wherein the sides are formed from a single piece of metal so arranged as to form a rigid shell;

Sixth, to provide a water cooler of this class which incorporates a novel means of securing and retaining the olla;

Seventh, to provide a water cooler of this class which is particularly simple and economical of manufacture and attractive in appearance; and

Eighth, to provide on the whole a novelly constructed cabinet water cooler which is durable, efficient in its action, and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a perspective view of my novel water cooler; Fig. 2 is an enlarged fragmentary sectional view thereof through 2—2 of Fig. 1, showing by dotted lines a water bottle in position thereon; Fig. 3 is a further enlarged transverse sectional view through 3—3 of Fig. 2, with parts and portions in elevation to facilitate the illustration; Fig. 4 is an enlarged fragmentary sectional view through 4—4 of Fig. 3, and Fig. 5 is a developed view of the shell member.

Similar characters of reference refer to similar parts and portions throughout the several views of the drawings.

Shell 1, supporting bars 2, journal rivets 3, clamp lugs 4, olla 5, cover 6, gaskets 7, faucet unit 8, drip pan 9, waste collector 10, cup tray 11, and

drain cock 12, constitute the principal parts and portions of my novel cabinet water cooler.

The cabinet water cooler is encased in a shell 1 which is preferably formed of sheet metal initially formed in the manner shown in Fig. 5. The metal is folded to form three sides, which the end portions form the fourth side; the ends being folded together along the center thereof, as indicated by 1a in Fig. 3. The bottom edge of the material is provided with upwardly directed notched portions 1b forming at the corners a plurality of legs 1c. Near the upper margin the shell member 1 is provided with a plurality of perforations 1d. It will thus be seen that the shell when formed is substantially square in section and relatively tall.

Extending between two opposite sides of the shell 1 is a pair of supporting bars 2. The supporting bars are substantially U-shaped in form and are arranged with their leg portions, designated 2a, extending outwardly and horizontally from each other towards the remaining sides of the shell, as shown best in Figs. 2 and 3. The extended portions of the legs 2a are rotatably secured to the shell 1 by means of journal rivets 3. The cross portions, designated 2b, of the supporting bars are arranged in spaced parallel relation and are provided with clamp lugs 4. There being provided a pair of clamp lugs on each cross bar 2b. The clamp lugs are arranged so as to define a circle. The supporting bars 2 are arranged to receive an olla 5 formed of suitable porous clay or the like having a substantially flat bottom 5a and straight side walls 5b. The weight of the olla 5 upon the supporting bars tends to push them downwardly but the clamp lugs 4 are thereby forced against the sides of the olla so as to securely hold it in centered relation within the shell. With this arrangement, ollas of various diameters may be accommodated by the supporting bars 2; a larger olla being held when the leg portions 2a are directed downwardly and outwardly, and a smaller olla than that illustrated being held when the leg portions 2a are extending upwardly and outwardly.

The olla 5 projects a short distance above the upper end of the shell 1. Fitted around the upper end of the olla 5 and resting on the shell 1 is a cover 6 which is provided with a substantially square lower end forming a narrow skirt 6a adapted to fit over the upper edge of the shell 1. The upper end of the cover 6 is provided with a circular opening of approximately the same diameter as the olla 5. Around this opening, designated 6b, the cover 6 is provided with

a channel 6c which receives a gasket 7. The gasket 7 may be in the form of a rubber tube and is adapted to support a water bottle B or the like. Within the cover 6 adjacent the opening 6b there may be formed a second channel 6d likewise provided with a gasket 7 adapted to engage the periphery of the olla 5 and form a substantially sealed connection between the olla and the cover. However, some air space must be provided in order to permit water to flow from the bottle into the olla.

Adjacent the lower end of the olla there is provided a faucet unit 8 which is secured to the olla and extends laterally therefrom through an aperture 1e formed in a side wall of the shell 1.

A drip pan 9 extends across the shell 1 below the supporting bars 2. The drip pan is relatively flat and is preferably spaced a slight distance from the front and rear sides of the shell but is larger in diameter than the olla 5. The drip pan is disposed so that its surface slopes downwardly towards the forward side of the shell 1, its center sloping at a greater angle than its sides so as to form a rudimentary spout portion 9a at the center of its forward edge, as shown in Figs. 2 and 3. The drip pan is provided with an opening 9b having a raised flange therearound. This opening is preferably centered with respect to the shell 1 and is relatively large in diameter. If the olla 5 is arranged with its bottom 5a dished upwardly a slight amount any moisture will tend to drip from the periphery of the olla rather than from a central portion so that no water will fall to the floor through the opening 9b.

A relatively deep receptacle of comparatively small section is provided. This receptacle forms a waste collector 10 and is mounted against the forward side of the shell 1 so as to catch any moisture that might drip from the pan 9. The waste collector 10 is held near its upper portion by means of a fitting 11a forming a part of a cup tray 11, and adjacent its lower portion by means of a fitting 12a forming a part of a drain cock 12. The cup tray 11 is cast or molded from any suitable material and is provided with a recess or basin portion 11b at its upper side. The above-mentioned fitting 11a is cast or formed as an insert in the tray 11 and is tubular so as to form a drain for the basin portion 11b, thus discharging liquid from the cup tray into the waste collector 10. It will be noted that the position of the tray is such that the collector 10 cannot overflow without overflowing through the cup tray, thereby warning one of its condition. The fitting 12a is likewise tubular so that water may be drained from the waste collector through the drain cock 12.

The shell 1 provides an elongated stack for controlling and aiding the flow of air around the olla 5. Air enters through the apertures 1d, evaporates water from the surface of the olla 5, and being laden therewith and somewhat cooler falls to the bottom of the shell 1 and outwardly along the floor. This action creates a pressure difference between the top and the bottom of the shell 1 so that a constant flow of air is main-

tained therethrough. Furthermore, the moist air after passing the olla is directed to the most favorable place in a room for receiving such air, namely, the floor, for here the air is colder and the heaviest.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a cabinet water cooler, a shell member open at its upper end, a cover for the upper end thereof having a centrally disposed aperture therein, a supporting ring member bordering said aperture at the upper extremity of said shell and arranged to engage and support a liquid reservoir, a receptacle support secured in said receptacle to the inside of the walls thereof near its middle portion, a receptacle adapted to rest upon and extending into contiguous relation to the margins of the aperture in the cover so as to receive liquid from said liquid reservoir, a faucet extending from the receptacle through a wall of the water receptacle, a basin fixture mounted below the faucet, a drain cock fixture mounted below the basin fixture, said fixtures including tubular securing elements protruding through the wall of the shell member, and a waste collecting vessel mounted wholly within the shell member and secured thereto by means of said securing elements whereby water from the basin drains therein and the drain cock forms an outlet therefor.

2. In a cabinet water cooler, a shell member open at its upper end, a cover for the upper end thereof having a centrally disposed aperture therein, a supporting ring member bordering said aperture at the upper extremity of said shell and arranged to engage and support a liquid reservoir, a receptacle support secured in said receptacle to the inside of the walls thereof near its middle portion, a receptacle adapted to rest upon and extending into contiguous relation to the margins of the aperture in the cover so as to receive liquid from said liquid reservoir, a faucet extending from the receptacle through a wall of the water receptacle, a basin fixture mounted below the faucet, a drain cock fixture mounted below the basin fixture, said fixtures including tubular securing elements protruding through the wall of the shell member, a waste collecting vessel mounted wholly within the shell member and secured thereto by means of said securing elements whereby water from the basin drains therein and the drain cock forms an outlet therefor, and a drain pan bridging the shell member below and adjacent the receptacle and above the vessel positioned on an angle directing drippings from the receptacle into said vessel.

CARTER F. TRUITT.
